United States Patent Office.

EDWIN CRAWLEY AND THOMAS L. BAYLIES, OF RICHMOND, INDIANA.

Letters Patent No. 89,469, dated April 27, 1869.

IMPROVED VISE.

The Schedule referred to in these Letters Patent and making part of the same.

To all whom it may concern:

Be it known that we, EDWIN CRAWLEY and THOMAS L. BAYLIES, of Richmond, in the county of Wayne, and State of Indiana, have invented a new and useful Improvement in Automatic Vises; and we do hereby declare that the following is a full, clear, and exact description of the same, reference being had to the annexed drawing, making part of this specification, in which—

Figure 1 is an elevation of our improved vise, showing the position the parts assume when the jaws are not pressing upon anything.

Figure 2 is an elevation, showing the position they assume when pressing an object which has been placed between them, or when they come in contact with each other.

Figure 3 is a perspective view of the nut, through which the tightening-screw passes.

Corresponding letters in the several figures represent corresponding parts.

This invention relates to an improvement in automatic vises, or that class of vises the moving jaw of which has a rapid motion, when being adjusted with reference to the object to be secured therein, but which has a slower motion, and an increased force imparted to it, when it comes in contact with the thing to be held; and

It consists in the combination and arrangement of the parts of which it is composed, as will be more fully described hereinafter.

A, in the drawings, represents the back, or fixed jaw of the vise, which is to be provided with the necessary projections for securing it to a bench, and at a suitable place, with reference to its length. It is to be provided with ears, A', which may be formed upon said jaw, or they may be made separate therefrom, and be secured to it by bolts, or rivets

At the point where these ears, or projections are joined to the jaw A, it is to be reduced in thickness, so that the space between such ears shall only be equal to the thickness of the jaw B, at the point where it enters between said ears.

B represents the outer, or movable jaw of the vise, which may be of wrought, or cast-metal, and provided with the projection B' upon its inner edge, for entering the space between the ears upon jaw A. It is to be of any required length, and is to have the usual aperture through its upper end for the passage of the tightening-screw.

C represents the tightening-screw, which may be of the usual construction, except that it is to have a much coarser thread than screws usually employed for such purposes, so that the jaw may have a more rapid motion than it does in ordinary vises. This arrangement is of great importance in vises of this construction, as it results in a considerable saving of time, inasmuch as, when the jaw is approaching or receding from the article to be clamped, its movement will be rapid, and, as the force to be applied does not depend entirely upon the screw, but upon the action of a series of levers in combination therewith, it follows that any required amount of compressing-force can be applied by it. This screw is to have the usual head upon its outer end, and is to be supplied with the usual handle, or lever for turning the same.

D represents the nut, through which screw C passes.

Upon each end of this nut journals may be formed, for the purpose of enabling it to fit within and control the movements of the lever E. The back side of this nut, or that portion of it which comes in contact with the stationary jaw of the vise, is slightly curved, or rounded, so as to insure its always having a fair bearing upon such jaw, when in contact therewith.

It will be seen, upon reference to fig. 2 of the drawings, that as lever E and nut D recede from the fixed jaw, the nut, in order that it may maintain its proper position with reference to the screw, must necessarily partially rotate upon the journals formed upon it, which is an additional function performed by such journals.

E represents a lever, which, when the jaws of the vise are not acting upon any article to hold the same, assumes the position shown in fig. 1, which is about in line with the inner edge of the fixed jaw A. The lower end of this lever passes between the ears, or projections A', and is pivoted to them at a point near their lower edges, while its upper bifurcated end extends to and embraces the nut D.

F represents an arm, or lever, which, in the present case, is pivoted to the movable jaw upon its edge, and at a point nearly opposite the centre of the tightening-screw, and extends, nearly in a line therewith, to a distance beyond the rear side of the fixed jaw A.

Upon that portion of the upper surface of this arm, or lever which comes opposite the fixed jaw, and for some distance each way therefrom, there are formed serrations, or teeth, which serve to receive the end of the pawl, or dog I, for a purpose to be hereinafter explained.

It will be observed, that this arm is provided with a slot, as shown at c, which is for the purpose of allowing it to travel back and forth with the jaw B, a screw passing through said slot, and into jaw A, for the purpose of retaining the back end of said lever in position during such movement.

We have shown and described this bar, or arm as attached to the edge of the jaws, but it is apparent that a slot may be formed through the jaws, and through the lever E, and this arm be passed through such slots, and made to work therein, and that these slots may be located at any desired point beneath the tightening-screw.

This last-named arrangement we prefer for some forms of vises, and especially for such as are made of wrought-iron, as in such cases, the forming of such slots will not endanger, to any great extent, the breaking of such jaws, and, as it will afford a more compact arrangement of the parts, and place them more completely out of the way, and where they would be less likely to be injured by falling weights.

G represents a spring, which is to be attached to the lower portion of the jaws, or to a projection formed thereon, for the purpose of acting upon such jaws for the purpose of separating their upper ends, as the tightening-screw is turned outward.

H represents a spring, which may be attached to the projections upon jaw A and lever E, which is elongated by the action of the screw in drawing the lever away from the jaw, but which, when the screw is turned in the opposite direction, will operate to draw said lever back to the position shown in fig. 1 of the drawings.

It is apparent that other forms of springs may be used for the purpose above described, and hence, we do not desire to be understood as limiting ourselves to the use of a spiral spring in this connection.

I represents a dog, or pawl, which is to be pivoted to the jaw A, at such a point as will permit its outer end to fall into and engage with teeth formed upon the upper surface of the arm, or lever F, for the purpose of bringing the lever F into action so soon as the jaws come in contact with the article to be held.

K represents a tripping-toe, which may be attached to the side of lever E, or it may have a projection upon its side, which may rest within the slot of such lever. In either case, it is to travel with said lever, and is for the purpose of tripping said pawl, it being so arranged with relation thereto, that when the jaws of the vise are to be separated for the purpose of receiving the article to be held, it will, by the action of spring H and lever E, raise the pawl out of the notches, or arm F, and thus permit jaw B to follow the movements of the screw.

The operation of our improved vise is as follows:

The parts being in the position shown in fig. 1, are ready for the reception of the article to be held. The pawl I, having been raised by the action of spring H and lever E, the article to be held is to be inserted between the jaws, and screw C turned in the proper direction, to cause the moving jaw to approach such article; and when it comes in contact therewith, the continued movement of screw C overcomes the tension of spring H, and the upper end of lever F commences to recede from jaw A; the first result of which is to cause the tripping-toe to recede from pawl I, and permit said pawl to engage with the teeth formed upon arm F, which has the effect to convert jaw B into a lever for the time, the fulcrum of which is at the point at which the arm F is pivoted to said jaw.

When the jaw B has been converted into a lever, by the above-described movement of the parts, the

projection B', upon its lower portion, is brought in contact with lever E by reason of the fact that lever E, so soon as it leaves its position in contact with jaw A, commences to approach this projection, and, when in contact therewith, serves as the moving power for what is now both lever and jaw B, thus forcing outward its lower end, which is guided in its movements by a screw working in a slot, b, formed in the ears upon jaw A.

As a consequence of the above arrangement of the levers F and B, a large increase of power is obtained by the further turning of screw C, as it is apparent that the distance from the point at which lever F is pivoted to jaw A, is nearer the point of its contact with its fulcrum on lever, or jaw B, than is the point at which the power is applied to said lever, thus leaving the long arm of such lever on the side of the applied force, and the short arm on the side of the resistance.

A still further increase of power is obtained by the operation of this long arm of lever E upon the lower or long arm of jaw, or lever B, its fulcrum, as before observed, being at the part at which arm F is pivoted to it, thus enabling lever E to press upon its long arm, and thus give to the vise a largely-increased power of compression over what could be obtained with a screw alone, while it possesses all the advantages of a rapidly-moving vise, when being opened or closed.

Having thus described our invention,

What we claim, and desire to secure by Letters Patent, is—

1. In combination with the jaw A, a movable jaw, B, lever E, nut D, and screw C, so arranged that the movable jaw and lever shall form a compound lever, operated by the screw for the compression of an article placed between the jaws, substantially in the manner set forth.

2. In combination with said parts set forth in the first clause of claim, the bar F, and pawl I, arranged to form an adjustable fulcrum for the jaw B, substantially as set forth.

3. The combination of the jaws A and B, screw C, lever E, and nut D, with an adjustable fulcrum and spring, H, so arranged that the movable jaw shall be actuated by the screw in closing upon an article placed between the jaws, until the increased resistance, causing the spring to yield, brings into action the united compressing-force of the screw and compound lever, substantially in the manner set forth.

4. The combination and arrangement of the jaws A and B, lever E, nut D, screw C, bar F, pawl I, and tripping-toe K, substantially as set forth.

In testimony whereof, we have signed our names to this specification, in the presence of two subscribing witnesses.

EDWIN CRAWLEY.
THOS. L. BAYLIES.
